FIG. 1.

FIG. 2.

FIG. 3.FIG. 4.

FIG. 1 is a perspective view of a window trim showing my new design, said trim being fragmentarily shown to indicate indeterminate length;

FIG. 2 is a sectional view taken along line 2-2 of FIG. 1;

FIG. 3 is a perspective view of the window trim showing my new design, but illustrates another embodiment thereof, said trim being fragmentarily shown to indicate indeterminate length; and

FIG. 4 is a view taken along line 4-4 of FIG. 3.

This is a continuation of design applications Ser. No. 382,727, filed July 26, 1973, and Ser. No. 433,303, filed Jan. 14, 1974, both now abandoned.

I claim:

The ornamental design for a window trim, substantially as shown and described.
